UNITED STATES PATENT OFFICE.

CHARLES H. MORRILL, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

METHOD OF MAKING RUBBER FOOTWEAR.

Application filed January 16, 1919. Serial No. 271,397.

To all whom it may concern:

Be it known that I, CHARLES H. MORRILL, a citizen of the United States, residing at Swampscott, in the county of Essex and State of Massachusetts, have invented certain Improvements in Methods of Making Rubber Footwear, of which the following description, in connection with the accompanying drawings, is a specification, like reference characters on the drawings indicating like parts in the several figures.

The present invention relates to improvements in the manufacture of rubber footwear and for convenience will be described in connection with the manufacture of that type of such footwear which is known as "overshoes" or "artics."

The upper or top of an artic ordinarily comprises two parts, a vamp constituting the forepart portion and a quarter constituting the heel and side portions of the artic and each of these parts is made up of a number of pieces of different materials such as an inner fleece lining, an intermediate reinforcing layer known as a collarette, and an outer fabric piece called cashmerette. These top pieces vary according to the grade of the artic to be made. In making the artic, the top has been produced by a "building-up" process in which the various top pieces are separately and successively relatively positioned and applied to a wooden form or last, the maker fitting and lapping the pieces as the process progresses. Thereafter the shoe bottoming materials, including the insole, filler, foxing and outersole, are applied to the form to build up the artic to the sole vulcanizing stage. By reason of the character of the operations performed, the artic, as heretofore made, is built entirely by hand makers who are necessarily skilled laborers. It will be appreciated that the procedure thus followed in making artics and similar types of shoes is dependent entirely upon the skill of the makers and that, even if skilled makers are employed, both the quality of the workmanship and the shoe production varies considerably. Poor workmanship is of great consequence in making rubber shoes since it is difficult to detect until after the shoe is completed where it invariably appears in a defective vulcanization at some place on the shoe. Indeed, even under the best conditions, a

considerable number of defective shoes or "seconds," which represent a serious loss to the manufacturer, are produced.

The present invention has for an object to provide an improved process of making artics and similar types of built-up shoes the practice of which will lessen the hand labor and the skilled operations heretofore attendant upon the making of such shoes and enable a more accurate and uniform production to be obtained at low manufacturing cost.

With this object in mind, the invention contemplates in one of its aspects, the preparation of a top for an artic which consists in cutting out pieces to constitute the vamp of an artic, including an inner fleece lining, one or more collarettes, and an outer cashmerette, and finally assembling them together, similarly preparing the quarter for the artic, uniting the assembled vamp and quarter, preferably, on opposite sides of the artic, to form a unitary top, assembling the said top and an insole on the form or last on which the artic is to be made and then performing subsequent operations to complete the manufacture of the shoe.

In the practice of the invention the top will conveniently be prepared and assembled as a unit in the cutting and stitching room and then sent to the making room to be assembled with the insole on the artic form or last for subsequent operation. Since the constituent pieces of the vamp and the pieces of the quarter may be assembled and the vamp and quarter united while the shoe top is flat and all parts of it are entirely accessible and may be readily manipulated, greater speed and accuracy in assembling the parts may be obtained, and also the top parts may be more readily and more uniformly secured together, as by rolling the overlapped cement coated portions into adhesion. Furthermore, the fitting and assembling of the vamp and quarter into a unit in this manner makes it feasible to employ unskilled labor without in any respect diminishing the quality of the product.

As herein set forth, the parts of the vamp and the quarter preferably will be so shaped and fitted that the vamp and quarter will overlap at opposite sides of the shoe at the shank, these overlapped portions being permanently secured together as by stitching.

Also, if desired, a reinforcing tab may be stitched to the joint or overlap to provide the desired strength at these places.

A further characteristic advantage is that

- 5 the present invention for the first time makes it not only possible but entirely practicable to stretch and shape the shoe top into conformation to its last end under tension, as by power operated lasting machinery.
- 10 In another aspect, therefore, the invention comprises assembling the prepared top, together with an insole, on a last, conforming the top to the last under tension as by applying a forward tension to the toe end of
- 15 the top and a tension simultaneously to opposite sides of the top, securing the margin of the top to the insole at the pulled over points, working the remaining portions of the last over on the insole to complete the
- 20 shaping of the top to the last, and thereafter applying a sole and performing subsequent operations in the usual manner. The application of forward tension to the toe end of the top and a tension simultaneously
- 25 to opposite sides of the top at the toe, is of especial advantage since thereby the top is first properly set lengthwise of the shoe form and then the vamp is pulled laterally into conformation to the form without undistortion of the top materials or displacement of the foot opening of the arctic. The side tension applied to the vamp also
- 30 pulls the vamp into the concaved instep portion of the form or last so that it and all
- 35 parts of the shoe are tensioned on the form and are brought into a sufficiently compact body to insure subsequent vulcanization of the shoe in the proper manner.

- In another aspect, the invention provides
- 40 for applying the "foxing" to the top prior to its being assembled on the last instead of applying the foxing to the sides of the top and overlapping it on the bottom of the arctic as heretofore. This foxing extends between
- 45 the fabric upper and the outersole to insure proper vulcanization of the outersole to the fabric upper and for this reason it necessarily consists of high grade rubber. By applying the foxing to the vamp as the constituent parts are being assembled together, the foxing may be readily rolled to insure its adhesion to the underlying portion of the vamp because the vamp at this time may be laid flat whereas under the present practice,
- 55 the foxing can not be rolled without considerable difficulty owing to the fact that as it is applied, it must be conformed to the various curvatures of the shoe form. As herein set forth, the foxing is only applied
- 60 to the vamp of the arctic top, the foxing for the quarter being applied after the shoe is lasted. In practice, this is found most convenient inasmuch as it enables the ends of the quarter foxing to cover the joining
- 65 between the vamp and the quarter. If de-

sired, however, the overlap may be covered by a separate piece.

Other objects and novel characteristics of the present invention will now be described in connection with the accompanying drawings which illustrate the preferred method of practising the invention and the invention will then be pointed out in the appended claims.

Fig. 1 is a perspective view showing the preparation of various pieces to constitute the vamp of an arctic shoe in accordance with one step in the preferred practice of the present invention;

Fig. 2 is a perspective view showing a similar preparation of the various pieces to constitute the quarter of the arctic;

Fig. 3 is a perspective view showing the vamp and the quarter of the top assembled and ready for application to a shoe form;

Fig. 4 is a perspective view illustrating the step of assembling the unitary top and an insole on the last;

Fig. 5 is a perspective view illustrating the step of shaping the prepared top to the form and attaching it in its shaped position to the insole;

Fig. 6 is a perspective view showing the arctic with the sole applied and finally prepared for vulcanization.

In carrying out the invention in one manner in which it has been successfully practised, a blank 2 of suitable shape to correspond to the vamp of the arctic is first provided, this blank being preferably made of fleece lining such as is now ordinarily used for the inner lining of arctic shoes. A quarter shaped blank 4 of fleece lining or similar material is also cut out to constitute the inner lining of the quarter. Collarettes 6 and 8 for the vamp and the quarter, respectively, are next cut out from friction cloth or similar rubberized cloth, the same material being used for the collarettes as with the prior methods. The outer cashmere pieces 10 and 12 for the vamp and the quarter respectively are also cut out in substantially the same shape as heretofore except at the rear portion of the vamp, the cashmere piece 10 is extended a distance to enable it to overlap a corresponding portion provided at the forward portions of the quarter as indicated at 14. The collarettes 6 and 8, which consist of semi-circular shaped bands of friction cloth, form the outer marginal portion of the top, together with the fleece linings 2 and 4, the cashmere pieces terminating a considerable distance away from the edge of the top. The quarter includes in addition to the fleece lining 4, the cashmere 12 and collarette 8, a junior 16 for stiffening the heel portion of the quarter, this junior consisting of relatively thin layer of cheap rubber compound such as rag stock. In the next step o

the process the constituent pieces of the vamp are fitted together, the inner fleece lining being arranged with the fleece side toward the inside of the shoe, the collarette placed 5 on the lining along its margin, and the cashmerette placed so as to constitute the outer layer of the top, the lower margin of the cashmerette piece overlapping the upper margin of the collarette. In assembling 10 these pieces they are cemented to each other throughout and after the vamp is made up it is conveniently rolled or pressed together to bring the pieces into proper adhesion for vulcanization, this rolling operation being 15 performed with greater facility and more uniformly and accurately than in the corresponding operation with the prior practice by reason of the fact that the vamp can be laid flat upon a table. Preferably also, 20 foxing 18 for the arctic is applied to the vamp before it is assembled on the form. This foxing, which consists of a strip of high grade rubber, is readily applied to the upper surface of the vamp in the usual 25 position, that is, with its upper edge overlapping the lower edge of the cashmerette as shown in the drawings. This foxing is also rolled into perfect adhesion with the underlying vamp materials, as by a small 30 hand roller, or the vamp including the foxing, may be rolled in a single operation. The upper edge of the foxing is preferably wheeled to form a line of small indentations in the foxing as illustrated in the drawings, 35 the wheeling operation acting to indent the foxing in the cloth and insure vulcanization of the foxing to the underlying fabric. The width of the foxing is such as to extend to the outer edge of the underlying vamp 40 materials. The parts which are to constitute the quarter are assembled together in the same manner that is followed in making up the vamp, and in addition the junior or heel stiffener 16 is placed between the collarette and the cashmerette as customary, 45 and a separate junior covering layer of friction fabric is applied. The assembled quarter is rolled in the same manner as the vamp to bring the various parts into proper adhesion relation. Preferably, however, a 50 foxing is not applied to the quarter as in the vamp for a reason hereinafter to be mentioned.

In the next step in the process the assembled vamp and assembled quarter are secured together to constitute a unitary or one-piece top for the arctic before it is applied to the form on which the arctic may be made. This is done by overlapping the 55 portions 14 formed on the quarter parts on to the corresponding portions on the vamp and then securing the overlapped portions together with a sewed seam 22 by a sewing machine in any desirable manner. A reinforcing tab may be applied to the overlapp- 60

ing portions of the vamp and quarter prior to connecting them together by the stitches 22 in order to reinforce the connection between the two parts. Alternatively, however, and as herein illustrated, the heel 70 collarette is made so as to overlap at that place. By following the practice above described, it will be seen that the maker is able to match up the various pieces which constitute the top flat, as distinguished from 75 applying them to a heavy form as with the prior method, and consequently the two parts may be assembled by unskilled help with considerable dexterity and accuracy. 80 One of the most serious difficulties encountered in the prior method is the rolling of the various pieces of the top into adhesion to insure perfect vulcanization. This is due to the fact that the building up process by which the pieces are assembled does not 85 afford conditions for them to be rolled conveniently. The operator ordinarily uses an iron roller for this purpose; but, because the form on which the top is supported is so irregular, only comparatively small portions of the top are treated without the exercise of considerable care and the expenditure of considerable time. With the 90 method herein involved, however, the finally assembled vamp and the quarter can be readily laid flat on a table and rolled or 95 rolled by passing between rolls of a suitable machine.

In the next step of the process the prepared top is assembled, together with an insole 24, upon a suitably-shaped wooden form or last 26, the bottom face of which is provided with a metal plate. This insole is made of a material of a texture which will 100 receive lasting tacks driven into it, and at the same time withstand the heat used in vulcanizing the shoe as, for example, a compressed felt or a suitably water-proofed layer of fiberoid. It is also preferable that the upper side of the insole be coated with 105 cement in order that the insole may receive the overlusted margin of the top and become consolidated with the bottoming materials used in making the shoe. 110

To enable the pulling-over and lasting operations which are to be performed to produce the best results and also to obtain the desired shape of the shoe bottom, this insole is preferably molded to the conformation of the bottom of the form. For arctic work the insole, as illustrated, has a decided break at the heel breast line 28 in order that the arctic may provide the necessary pocket to receive the heel of the shoe when the arctic is being worn. The molded insole is 115 secured to the last by two or three tacks in the forepart, shank and heel and the shoe then presented to a machine which is adapted first to apply tension to the toe portion of the top and a tension simultaneously 120

125

130

to opposite sides of the blank at the toe. A machine which can advantageously be used for this purpose is shown in United States Letters Patent No. 663,777, granted Dec. 11, 1900 on application of Ronald F. McFeely. This machine is provided with a set of grippers 29 arranged to seize the upper at the toe end of the last and another set of grippers 30 arranged to seize the blank at opposite sides of the toe and in the first cycle of its operation a forward tension is applied to the toe end of the upper so as to draw the upper firmly against the heel of the last and draft the upper longitudinally about the last and then exert a tension simultaneously on opposite sides of the upper to draw the blank into the concaved instep portion of the last. Subsequent cycles of operation of the machine carry the seized marginal portions 5 of the blank over on the insole and while under tension secure the blank to the insole by a plurality of tacks driven at the pulled-over portions of the top along the sides and at the toe. By reason of the stitched connection between the vamp and the quarter it is possible in the pulling-over operation to exert a considerable tension on the upper and pull it down tightly to the conformation of the last without distorting or otherwise injuring the upper.

Following the pulling-over operation the remaining portions of the blank are worked over on the insole and secured in lasted position to complete the shaping of the top to the form. Conveniently and advantageously these remaining portions of the blank are lasted by a machine of the well-known "hand method" lasting machine type which operates by repeated progressive operations of the gripper 34 to seize the marginal portion of the top, tension it about the last and then carry the margin 5 over on the insole 24 and secure it by the lasting tacks 32. Owing to the molded formation of the insole both the pulling-over and lasting operations on the arctic are facilitated and the margin of the upper, tacked down on the insole firmly and accurately. The upper is, of course, held firmly in lasted position on the insole by the tacks which have been referred to. Both of these machine operations on the shoe will be performed in such manner that each shoe is shaped to the form 26 accurately and uniformly and at a speed which compares favorably with hand work without involving the element of variation in quality and quantity of work which is a frequent accompaniment of hand labor.

Preferrably, and as herein illustrated, a foxing 35 is applied around the heel end of the shoe after the shoe has been lasted to the innersole or, as herein described, pulled-over and lasted, inasmuch as it is found more convenient to apply the foxing to the

quarter at this time rather than to apply the foxing to the quarter before it is assembled on the last. Moreover, the forward ends of the foxing may be carried over the stitches 22, connecting the quarter with the vamp at this time, and the foxing conformed more accurately and uniformly to the contour assumed by the quarter on the form. While it is preferable, as herein set forth, to apply the vamp foxing 18 to the vamp before the vamp and quarter are assembled together and the quarter foxing after the arctic is lasted to the insole, the invention is not limited to this procedure, but comprehends any application of the foxing which may be found most desirable either before or after the prepared top is assembled on the form.

After the margin 5 of the top has been lasted on to the innersole and secured in position by the tacks 32, subsequent operations on the shoe to complete its manufacture are performed in the usual manner. These operations ordinarily include applying a filler piece to the bottom of the shoe, the filler piece fitting within the overlasted margin of the top, app'ying a binder to the shoe bottom and then an outsole 28 to the shoe, the entire shoe bottom thereafter being rolled or pressed to bring the bottoming materials into proper adhesion for vulcanization. Thereafter the shoe is vulcanized in any preferred manner. Owing to the steps followed in making the shoe, and particularly in preparing the top for application to the form, the shoe vulcanizes uniformly and completely and without producing the number of defective shoes or "seconds" which were incident to the prior methods of making shoes. It will be observed that by the practice of the method herein set forth the labor or production cost of making arctic and similar rubber shoes is reduced and the product obtained superior to the hand-made shoes both in appearance and in the fit and the wearing qualities of the shoes.

It is to be understood that the herein described method is not limited to a vulcanized shoe having a two-part top as a vamp and a quarter, but is of general applicability to all types of rubber footwear which have heretofore been made by separately applying to a form the various pieces of shoe parts which are to constitute the shoe.

Having thus described my invention, what I claim as new and desire to secure by Letters Patent of the United States is:—

1. That improvement in methods of making arctic shoes which consists in cutting out pieces to constitute the vamp of the arctic, including the lining, a cashmerette and a collarette; cutting out pieces to constitute the quarter of the arctic, including a lining, a collarette, a cashmerette and a

junior, assembling the pieces of the vamp and the pieces of the quarter, uniting the vamp and the quarter into an assembled top unit, subsequently assembling the unitary top and an insole upon a form, and thereafter attaching the margin of the top to an insole and performing subsequent operations to complete the shoe.

2. That improvement in methods of making arctic shoes which consists in cutting out the pieces to constitute the vamp of the arctic including a lining, a cashmerette and a collarette; cutting out the pieces to constitute the quarter including a lining, a 15 collarette, cashmerette and junior; said pieces having adhesive coated portions, fitting together the said pieces of the vamp and the quarter into a single unitary top and pressing together the said pieces to 20 secure uniform adhesion of the pieces in fitted positions, subsequently assembling the unitary top with an insole upon a form, and thereafter attaching the margin of the top to the said insole and performing subsequent operations to complete the shoe.

3. That improvement in methods of making arctic shoes which consists in cutting out pieces to constitute the vamp of the arctic including a lining, a cashmerette, 30 and a collarette; cutting out the pieces to constitute the quarter including a lining, a collarette, a cashmerette and a junior, fitting the pieces of the vamp and the pieces 35 of the quarter; overlapping portions of the vamp and the quarter at either side of the shoe and stitching them together to constitute a unitary top, subsequently assembling the unitary top with an insole upon a form, and thereafter attaching the margin of the top to the insole and performing subsequent operations to complete the shoe.

4. That improvement in methods of making arctic shoes which consists in cutting out pieces to constitute the vamp of the shoe 45 including a lining, a collarette and a cashmerette, said pieces having adhesive coated portions overlapping the adhesive coated portions of the said pieces together in assembled relation and pressing said portions 50 together to secure adhesion between the said pieces, similarly making up a quarter for the arctic, stitching together the made-up vamp and the made-up quarter to form a unitary top, subsequently assembling the 55 unitary top with an insole upon a last, and thereafter attaching the margin of the top to the insole and performing subsequent operations to complete the shoe.

5. That improvement in methods of making arctic shoes which consists in cutting out the pieces which are to constitute the vamp of the arctic including the lining, the collarette, and the cashmerette, matching the said pieces together with cement and 60 rolling assembled pieces to effect adhesion,

applying a foxing to the upper marginal surface of the assembled vamp, similarly cutting out and matching together pieces to constitute a quarter of the arctic, securing the made-up vamp and the made-up 70 quarter together at opposite sides to produce a unitary top, subsequently assembling the unitary top together with an insole upon a last, and thereafter attaching the margin of the top to the insole and performing 75 subsequent operations to complete the shoe.

6. That improvement in methods of making arctic shoes which consists in cutting out pieces to constitute the vamp of the arctic including a lining, a cashmerette, and 80 a collarette; cutting out pieces to constitute the shoe quarter including a lining, a collarette, a cashmerette and a junior, assembling the pieces of the vamp and the pieces of the quarter; uniting the assembled vamp 85 and the assembled quarter at opposite sides, subsequently assembling the unitary top with an insole upon a last and securing the top to the last at the heel end tensioning the toe end of the top forwardly, and simultaneously tensioning the top at opposite 90 sides of the toe, securing the tensioned top to the insole around the toe, conforming the remaining portions of the top to the last under tension and securing them to the insole, and thereafter applying an outsole to 95 the shoe bottom and vulcanizing the shoe.

7. That improvement in methods of making arctic shoes which consists in cutting out pieces to constitute the vamp of the 100 arctic including a lining, a cashmerette and a collarette; cutting out the pieces to constitute the quarter including a lining, a collarette, a cashmerette and a junior; fitting together the said pieces of the vamp and 105 the said pieces of the quarter and uniting the vamp and the quarter at opposite sides of the shoe into a unitary top, subsequently assembling the unitary top and an insole upon a last, pulling-over the top to 110 shape it to the last and securing the top in pulled over position to the insole, lasting the remaining portions of the top and securing them in lasted position on the insole and thereafter applying an outsole to 115 the shoe bottom and vulcanizing the shoe.

8. That improvement in methods of making arctic shoes which consists in cutting out pieces to constitute the vamp of the arctic, including a lining, a cashmerette and a collarette; cutting out the pieces to constitute the quarter including a lining, a collarette, a cashmerette and a junior; fitting together the said pieces of the vamp and the said 120 pieces of the quarter, uniting the fitted vamp and the fitted quarter into a single top portion at opposite sides of the shoe, subsequently assembling the said top portion with an insole upon a last, seizing the toe portion of the vamp at opposite sides of 125 130

the vamp and pulling the top lengthwise of the insole and simultaneously at opposite sides of the insole to conform the top to the instep and toe portion of the last and 5 securing the tensioned portions to the insole, progressively lasting the remaining portions of the vamp and securing the lasted portion to the insole, leveling the bottom of the shoe, and thereafter applying shoe bottoming materials to the shoe and vulcanizing it in the usual manner.

9. That improvement in methods of making arctic shoes which consists in cutting out pieces constituting the vamp of the 15 arctic including a lining, a collarette, and a cashmerette; cutting out pieces to constitute the quarter of an arctic including a lining, a collarette, and cashmerette and a junior; fitting together the pieces of the 20 vamp and the pieces of the quarter, uniting the vamp and the quarter into an assembled top unit, subsequently assembling the unitary top and an insole upon a form, shaping the top to the conformation of the form 25 and working the marginal portion of the top into lasted position on the insole, and thereafter applying an outsole to the shoe bottom and vulcanizing the shoe.

10. That improvement in the art of making rubber or rubberized footwear which 30 comprises cutting out a number of properly shaped pieces composed of or containing unvulcanized rubber including outer members and lining members, superposing such 35 members as are designed to be superposed, pressing them together while flat, uniting the members to form the closed upper of a shoe, assembling the closed upper, together with an insole, upon a last, lasting the upper, laying an outsole and vulcanizing the shoe.

11. That improvement in the art of making rubber or rubberized footwear which 45 comprises cutting out the pieces which are to constitute the vamp and those which are to constitute the quarter, building up the 50 vamp by superposing the pieces thereof one upon another and pressing them together while flat, building up the quarter in the same manner, fastening the quarter and vamp together to form a closed upper, assembling the closed upper together with an insole upon a last, lasting the upper, laying an outsole and vulcanizing the shoe.

12. A method of making footwear comprising vamp and quarter members each of a plurality of pieces of cloth and rubber capable of union by vulcanization, which consists in superposing the pieces of the vamp, 60 superposing the pieces of the quarter, uniting the quarter and vamp thus formed to provide an upper, drawing the upper upon a last and securing it to a sole, and finally subjecting the article to vulcanization.

13. A method of making footwear com-

prising vamp and quarter members each of a plurality of pieces of cloth and rubber, which consists in superposing and cementing together the pieces of the vamp, superposing and cementing together the pieces of 70 the quarter, securing together the quarter and vamp thus formed to provide an upper, lasting the upper and connecting it to a sole, and subjecting the article to vulcanization.

14. The method of making footwear comprising vamp and quarter members each of a plurality of pieces of cloth and rubber, which consists in superposing the pieces of the quarter in the flat and uniting them by adhesion, similarly superposing and uniting the pieces of the vamp, securing the quarter and vamp together to form an upper, lasting the upper and connecting it to a sole, and subjecting the article to vulcanization.

15. The method of making footwear comprising vamp and quarter members of a plurality of pieces of rubberized cloth and of rubber, capable of union by vulcanization, which consists in superposing the 90 pieces of the quarter, subjecting the assembled quarter pieces to pressure thereby uniting them through adhesion, and similarly superposing and uniting the parts of the vamp, securing the quarter and vamp 95 together to form an upper, drawing the upper upon a last and connecting it to a sole, and subjecting the article to vulcanization.

16. In a method of making footwear comprising vamp and quarter members each of a plurality of pieces of rubberized cloth and rubber capable of union by vulcanization, the step of superposing the pieces of the quarter, subjecting the said pieces to pressure whereby they are united through adhesion, and similarly superposing and uniting the parts of the vamp, and securing the quarter and vamp together to form an upper for lasting to a sole.

17. The method of making footwear comprising vamp and quarter members each of a plurality of pieces of cloth and rubber capable of union by vulcanization, which consists in superposing the pieces of the quarter with the omission of a heel foxing, superposing the parts of the vamp, overlapping the aforesaid parts of the quarter upon the vamp and securing the vamp to the quarter by stitching, and covering the 115 lines of stitching by a heel foxing.

18. The method of making footwear comprising vamp and quarter members each of a plurality of pieces of cloth and rubber capable of union by vulcanization, which consists in superposing the pieces of the quarter, superposing the pieces of the vamp, securing quarter and vamp together by stitching to form an upper, drawing the 120 upper upon a last and connecting it to a 130 upper upon a last and connecting it to a

sole, and subjecting the article to vulcanization.

19. As a new article of manufacture, an upper for lasting to a sole to form footwear, comprising vamp and quarter members each of a plurality of pieces of cloth and rubber united by adhesion and capable of permanent union by vulcanization, the said vamp and quarter members being connected together.

20. As a new article of manufacture, an upper for lasting to a sole to form footwear, comprising a vamp lining, an inner waterproofing vamp member, a cloth vamp and a rubber toe foxing, the said pieces being united together by vulcanizable adhesive and forming the vamp, and a quarter lining, a counter, a collar, a quarter member and a rubber heel foxing united together

by vulcanizable adhesive and forming a quarter, the vamp and quarter being connected together.

21. As a new article of manufacture, an upper for footwear, comprising vamp and quarter members each of a plurality of united pieces of cloth and rubber capable of union by vulcanization, and the two being connected together, the said upper being characterized by the fact that the superposed united pieces of both quarter and vamp are disposed in assembled relationship without tension upon or distortion of the threads of the fabric incorporated therein.

In testimony whereof I have signed my name to this specification.

CHARLES H. MORRILL.
